RAM PROTECTOR

Tom F. Larsen, Traer, Iowa

Application September 8, 1938, Serial No. 229,011

2 Claims. (Cl. 119—143)

This invention relates to a ram protector or means adapted to be worn by a ram to prevent sexual intercourse with ewes, when desired, rather than resorting to penning up the ram for long periods of time, as is customary and which is harmful to the ram.

A particular object is to provide a structure which will not chafe or harm the ram and one which is readily removable and which will be effectively positioned through the aid of the wool.

The more specific objects and advantages will become apparent from a consideration of the description following taken in connection with the accompanying drawing illustrating an operative embodiment.

In said drawing:

Figure 1 is a view showing my improvements in place on a ram, the latter being suggested in dotted lines;

20 Figure 2 is a plan view of the protector;

Figure 3 is a fragmentary edge elevation of the protector, and

Figure 4 is a cross sectional view through the protector taken on the line 4—4 of Figure 2.

25 Referring specifically to the drawing wherein like reference characters designate like or similar parts, 10 designates an attaching sheet or body adapted to encircle the body of the ram as shown in Figure 1. This sheet 10 for example may be 30 made of ordinary metallic chicken wire or it may be made of any other desired material, preferably mesh material, either metallic, textile or otherwise. Such sheet or body 10 being flexible, readily conforms to the contour of the body of the 35 animal and adjacent one corner thereof a flexible cord or lace member 11 is anchored, which may be of wire or textile material. When the ends of the sheet 10 meet around the body of the animal, the lace 11 is threaded through the adjacent meshes at one end, thus securing the ends 40 together and making an endless body about the body of the animal. Attention is also called to the fact that the lacing is not the only means to

hold the sheet in place, since the wool will grow around the wire or textile of the fabric, passing through the meshes thereof and holding the sheet in place, but at the same time permitting its removal.

Carried by the body of sheet 10 is a drain or pan 12, for instance of tin, which is substantially half funnel-shaped, having flanges 13 whereby it is fastened to the sheet 10. The drain 12 tapers, increasing in width in rearward direction. 10

Said drain 12 is located, as shown in Figure 1, adjacent the male organ of the ram, shielding it against sexual use and being positioned so that any discharge will be into the drain 12 from which the fluid will travel in a rearward direction. 15

Various changes may be resorted to provided they fall within the spirit and scope of the invention.

I claim as my invention:

1. A device of the class described having a body 20 to be secured about the body of an animal, said body consisting of flexible material having meshes of such multiplicity and size that substantially all of the wool covered by the body will grow therethrough unhampered, an imperforate drain carried by the body dispositioned adjacent the organ of the animal, said drain having a channel increasing in width in rearward direction, and flange means on the drain connecting it to the body, said body being metallic and flexible. 25

2. A device of the class described having a body to be secured about the body of an animal, said body consisting of flexible material having meshes of such multiplicity and size that substantially all of the wool covered by the body will grow therethrough unhampered, an imperforate drain carried by the body dispositioned adjacent the organ of the animal, said drain having a channel increasing in width in rearward direction, and flange means on the drain connecting it to the body, said body being of chicken wire. 35 40

TOM F. LARSEN.
